(57) **CLAIM**

The ornamental design for a docking station with dust collector for cleaning robot, as shown and described.

DESCRIPTION

The patent or application file contains at least one drawing executed in color. Copies of this patent or patent application publication with color drawing(s) will be provided by the Office upon request and payment of the necessary fee.

1.1 is a front view of a docking station with dust collector for cleaning robot, showing our new design;

1.2 is a rear view thereof;

1.3 is a left view thereof;

1.4 is a right view thereof;

1.5 is a top view thereof;

1.6 is a bottom view thereof;

1.7 is a front, top perspective view thereof;

1.8 is a rear, top perspective view thereof; and

1.9 is a rear, bottom perspective view thereof.

The yellow portions in the reproductions depict portions of the docking station with dust collector for cleaning robot that form no part of the claimed design.
